United States Patent Office

Des. 221,767
Patented Sept. 7, 1971

221,767

TELEPHONE DESK STAND

Donald M. Genaro, Haworth, N.J., John Niel McGarvey, Drexel Hill, Pa., Rembert Ryan Stokes, Middletown, N.J., and Gordon Elliot Sylvester, Jamaica, N.Y., assignors to Bell Telephone Laboratories, Incorporated, Murray Hill and Berkeley Heights, N.J.

Filed July 15, 1970, Ser. No. 23,963

Term of patent 14 years

Int. Cl. D14—03

U.S. Cl. D26—14

FIG. 2

In the drawing:

FIG. 1 is a perspective view showing the front and left side of the desk stand; and

FIG. 2 is a perspective view showing the rear and right side of the desk stand.

We claim:

The ornamental design for a telephone desk stand, substantially as shown and described.
